SAFETY HOISTING HOOK.

Application filed April 6, 1926. Serial No. 100,019.

My invention relates to hoisting hooks and has for its object the provision of a safety hoisting hook of improved construction.

Hoisting hooks are used on hoisting apparatus of various kinds, such for example as derricks, cranes and the like for facilitating the connection of the load to be lifted with the hoisting element such as a cable or chain. In hoisting or lowering cargoes from the holds of vessels with the usual open hook the point of the hook is liable to catch in the hatchway and cause inconvenience and loss of time. Moreover, in such an event, unless the hoisting gear is properly manipulated by the operator, there is danger of the load becoming released from the hook in one way or another. Although such an occurrence may at first seem rather improbable, nevertheless accidents of this kind are not uncommon and have in the past resulted in loss of life, not to mention the property damage to the load, the vessel or the wharf. The open hoisting hook is likely to engage the hatchway not only while the hook is being raised or lowered, but one of the frequent sources of this difficulty occurs when a load has been raised part way out of the hold and the hoisting stopped for some reason leaving the load suspended in mid-air. The open hook not infrequently stops at the same level with the hatchway or one of the decks and, in the slow lateral swinging of the load which invariably takes place, is very apt to become undesirably engaged with such a stationary member.

In constructing safety hooks of this kind, perhaps the most important consideration next to effectively preventing the hook from becoming undesirably engaged with stationary parts, is the provision of a construction which is not too complicated in its manipulation. The stevedores or other crane followers who do the work of attaching and removing the load from the hoisting hook many times work on the piece rate system and refuse to use a hook which increases to any material extent the amount of time required to place upon or remove a sling from the hook. Furthermore, the regulations of their unions uphold them in this attitude. The men themselves seem to disregard the added safety which can be secured.

The safety hook of my invention, because of its particular construction, accomplishes

both of these ends satisfactorily. It is an impossibility for the hook when closed to become engaged with any stationary object in such a way as to accidentally discharge its load. In fact, when the hook is closed it presents a smooth and continuous exterior surface at all points. The hook, however, is easily opened and when the keeper or guard member is in the open position the entrance to the hook is unobstructed so that there is no interference with the insertion or removal of the sling. In addition, the particular construction of my improved lifting hook avoids the possibility of the sling escaping from the hook, even when the sling and cable are slack, unless it is released by hand manipulation of the hook. With these several advantages the hook possesses the same degree of strength as other hooks and its structure is such that it can be manufactured commercially and at a reasonable cost.

According to the invention the shank of the hook member is provided with a locking aperture and a guard member, keeper, or tongue is pivoted on the shank and normally closes the hook by engagement with the point of the hook. The guard member itself is provided with an elongated opening adapted to register with the locking aperture in the shank when the guard member is in the closed position. A link, clevis, eye, or other shackle engages the shank for supporting the hook and passes through both of the registering openings, thereby locking the guard member in the closed position. With the parts in this relation the guard member is immovable either inwardly or outwardly although the guard member and the point of the hook are ordinarily so shaped that the guard member is prevented from moving inwardly by contact with the hook point. In order to open the hook when it is not supporting a load the link is movable in the elongated opening of the guard member out of locking relation with the locking aperture in the shank and this allows the guard member to be moved by hand outwardly, carrying the link in its elongated slot-like opening, and the guard member rotates about its pivot a sufficient distance to leave the opening of the hook entirely unobstructed so that a sling, bail or other means of fastening a load to the hook may be inserted or removed.

Further, in accordance with the invention the locking aperture in the shank, and the link member are so constructed that the link is movable out of locking relation with the aperture in the shank as above mentioned only when the link is in a predetermined position. Thus, for example in order to move the link out of locking relation with the locking aperture on the shank it is necessary first to turn the link through a predetermined angle, either in the plane of the link or in the vertical plane at right angles thereto or both. In this way the link must be moved to a predetermined non-load carrying position before the bottom of the link can be moved out of locking relation with the locking aperture in the shank, and to accomplish this the outlet of the locking aperture is restricted and the link is made of oblong cross section at one or more points in its periphery.

A better understanding of the invention will be had from an inspection of the accompanying drawings illustrating by way of example the preferred embodiment thereof, together with one modification. In these drawings

Figs. 1, 2 and 3 show the hook in closed position, Fig. 1 being a side view, Fig. 2 a front view, and Fig. 3 a rear view;

Fig. 4 is a side view partly in section showing the relation of the parts just after the guard member has been unlocked but before it is moved into wide-open position;

Figs. 5, 6 and 7 are perspective views showing three modifications of the link; and

Fig. 8 is a side view of a modified form of hook member.

Referring now to these drawings, the hook 10 has a point 11 and a shank 12 and shank 12 is provided with a transverse aperture 13 slightly longer in the vertical direction than in the horizontal, formed in this case by curving the end of the shank toward the point 11 of the hook, and serving both as a means for supporting the hook and as a locking aperture as will presently appear. This hook member is constructed of suitable material to give the required strength, usually being drop-forged from steel.

The guard member 14 for closing the hook opening is pivoted on the shank 12 by means of the pin 15, being bifurcated at its upper end as best shown in Fig. 2 with the ears 16 extending upwardly from the body of the member for engagement with the pin. The lower end of member 14 is of round or elliptical cross section similar to the form of the hook 10 and preferably terminates in a sloping point 17 which is adapted to contact with the point 11 of the hook which is correspondingly sloped for this purpose so as to limit the inward movement of the guard member 14. The guard member, not carrying any load, is usually made of metal which is less

strong than that required in the hook 10 such, for example as cast steel or bronze. For the pin 15, however, a corrosion-resistant metal such, for example as Tobin bronze is desirable as this prevents the jamming of the guard member 14 by rust through exposure to damp corrosive atmospheres in which the hook is most generally used.

The ears 16 of the guard member extend transversely some distance toward the rear of the hook, as may be seen in Figs. 1 and 4, around the opposite sides of the shank 12, and are each provided with elongated slot-like apertures 18 which are in transverse alignment with one another. In the closed position of the hook, that is with the guard member 14 as shown in Fig. 1 the vertical walls of the elongated openings 18 are in substantial registry with the vertical walls of the transverse locking aperture 13 in the shank 12. The upper walls of the elongated openings 18 are slightly above the top wall of locking aperture 13 so that the weight of the hook and its load will be taken entirely on the link 19, the bottom 20 of which passes through the registering openings 13 and 18.

It will be understood from the above that the bottom member 20 of link 19 passing through the registering openings 13 and 18 locks the guard member 14 in the closed position where it is impossible to move it either inwardly or outwardly except by a relatively small amount, depending upon the tolerances necessary for practical manufacture. It will also be understood that the weight carried by the hook is not taken by the ears 16 of the guard member but entirely by the shank 12 of the hook. Inasmuch as the locking of the guard member 14 is secured by the coacting link and registering openings, the position of the pivot pin 15 may be varied considerably. Thus, although it is convenient to place the pin at the front of the shank as shown in Figs. 1 and 4, it may also be placed mid-way of the shank 110 on the center line of the link 19 provided the link is made sufficiently wide that the head of the pin will not interfere with the free motion of the hook upon the link. Also pin 15 may be placed to the right of link 115 19 if desired, but the position at the left of the link as shown in the drawings is preferable because this permits the bottom 20 of the hook to easily clear the end of the shank when the hook is opened in the manner now to be described.

To open the hook for the insertion or removal of a sling, the cable having been slackened so as to remove the load from the hook, the bottom 20 of the link is lowered relative to the hook 10, the bottom moving toward the lower part of the elongated openings 18. When this movement has taken place, the bottom 20 will have moved out of locking relation with the locking aperture 13 130

and the guard member 14 together with the link 19 can be moved to the left as shown in Fig. 4, the bottom 20 clearing the point 21 of the shank 12. It will be observed, however, that the movement of the bottom of the link to the lower part of elongated openings 18 is obstructed by the restricted outlet 22 of locking aperture 13 caused by the presence of the projection 23, the horizontal width of bottom member 20 being greater than the width of outlet 22. Before being able to open the hook it is therefore necessary to rotate link 19 out of the vertical position far enough to permit the flattened side 24 thereof to pass through outlet 22. As shown in Figs. 1 to 4 inclusive it is necessary to rotate link 19 approximately to the horizontal position before the bottom 20 thereof will drop into the lower end of elongated openings 18. As soon as this takes place, however, guard member 14 may be pulled outwardly by hand as shown in Fig. 4 and rotated about pin 15 until it points almost straight upward when the entrance to hook 10 will be unrestricted in any manner by any portion of guard member 14. In Fig. 4 the opening of the guard member has just commenced. After one sling has been removed and another inserted on the hook 10 a reversal of the operations just mentioned replaces the bottom 20 of link 19 within the locking aperture 13, closing guard member 14 and locking it closed by means of the registering locking apertures.

By providing the restricted outlet 22 and making the link 19 of appropriate cross section to pass this aperture at a certain predetermined point only, the accidental opening of the hook is rendered impossible, and the hook can be opened only by manual operation. In the form of link 19 shown in Figs. 1 to 5 and described above the oblong cross section or flattened portion 24 is placed in the bottom 20 of the link and the link rotated in the vertical plane at right angles to the plane of the link in order to bring the link into position for opening the hook.

Figs. 6 and 7 show two modified forms of links which operate in a similar but slightly different manner from that just described.

With a link having an oblong cross section placed as shown at 25 it is necessary to rotate the link in its own vertical plane out of the load carrying position so as to bring the side of the link within the registering locking openings 13 and 18 in order to allow the link to drop to the bottom of elongated openings 18. When a link is used having an oblong cross section placed as shown at 26 it is necessary first to rotate the link in its own vertical plane to bring the side of the link into the registering openings 13 and 18, and then to rotate the link in a plane at right angles to the plane of the link in order to allow the oblong cross section 26 to pass the re-

stricted outlet 22 so as to bring the parts into position to open the guard member 14.

In the modified form of hook member shown in Fig. 8 locking aperture 13' is not provided with the restricted outlet 22, the projection 23 being omitted. In this form of hook the guard member 14 is pivoted to the pin 15' and the elongated openings 18 register with the locking aperture 13' when the guard member is in the closed position. Aside from the omission of the restricted outlet 22 the construction of the safety hook is entirely similar to that previously described. This modified form of hook has the same advantages as the hook described in Figs. 1 to 6 inclusive as far as the locking of the guard member 14 is concerned as long as the hoisting cable has no slack in it. However, with the modified form shown in Fig. 7 the link drops to the bottom of elongated openings 18 as soon as a relatively small amount of slack exists in the cable and from that time on the guard member 14 is unlocked and there is some likelihood of the link 19, or the sling itself forcing the guard member open. There are times when this is undesirable.

The improved safety hook of this invention is of such construction that the sling is at all times securely locked within the hook and it is impossible for the hook to catch or engage stationary objects during the hoisting or lowering operations. Moreover, because of the particularly simple structure the slings can be easily and quickly inserted or removed from the hook so that the use of the improved hook is not objectionable to workmen. In addition to its use in connection with cargo hoisting the improved safety hook can also be used for the Davit blocks of life boats, ferry boat chains, in piano and safe hoisting, in industrial crane work, and in general hoisting of all kinds, and it can be used in connection with both upper and lower blocks. Other specific examples showing various uses for the hook are as follows: painters' scaffolds and scaffolding generally, contractors' buckets, stone hoisting, steel erection, and drag hooks for drag chains.

I claim:

1. A lifting hook comprising a hook member having a shank provided with a locking aperture, a guard member pivoted on the shank and normally engaging the point of the hook to close the hook opening, the guard member being provided with an elongated opening which, in the closed position of the member, registers with the locking aperture in the shank, and a link engaging the shank for supporting the hook and passing through both of said registering openings so as to lock the guard member in said closed position, said link being movable in the elongated opening of the guard member out of locking relation with

the locking aperture in the shank when the hook is not supporting a load so as to allow the guard member to be moved outwardly to open the hook for the insertion or removal of a sling.

2. A lifting hook comprising a hook member having a shank provided with an oblong substantially vertical locking aperture, a guard member pivoted on the shank and normally engaging the point of the hook to close the hook opening, a guard member being provided with a slot substantially longer than the oblong locking aperture in the shank which, in the closed position of the member, registers with said locking aperture, and a link passing through both of said registering openings for supporting the hook and locking the guard member in said closed position, said link being movable to the bottom of the slot in the guard member when the hook is not supporting the load, and in such position being out of locking relation with the locking aperture in the shank thus allowing the guard member to be moved outwardly to open the hook for the insertion or removal of a sling.

3. A lifting hook comprising a hook member having a shank, the end of which is recurved toward the point of the hook to form a substantially vertical slot open at its lower end, a guard member pivoted on the shank and normally engaging the point of the hook to close the hook opening, the guard member being provided with an elongated opening which, in the closed position of the member, registers with the slot in the shank, and a link engaging the shank for supporting the hook and passing through both of said registering openings so as to lock the guard member in said closed position, said link being movable in the elongated opening of the guard member out of the lower end of the slot in the shank when the hook is not supporting a load so as to allow the guard member to be moved outwardly to open the hook for the insertion or removal of a sling, the link clearing

the recurved end of the shank during said movement.

4. A lifting hook comprising a hook member having a shank provided with a locking aperture, a guard member pivoted on the shank and normally engaging the point of the hook to close the hook opening, the guard member being provided with an elongated opening which, in the closed position of the member, registers with the locking aperture in the shank, and a link engaging the shank for supporting the hook and passing through both of said registering openings so as to lock the guard member in said closed position, said link when in a predetermined non-load carrying position being movable in the elongated opening of the guard member out of locking relation with the locking aperture in the shank so as to allow the guard member to be moved outwardly to open the hook for the insertion or removal of a sling.

5. A lifting hook comprising a hook member having a shank provided with a locking aperture having a restricted outlet, a guard member pivoted on the shank and normally engaging the point of the hook to close the hook opening, the guard member being provided with an elongated opening which, in the closed position of the member, registers with the locking aperture in the shank, and a link engaging the shank for supporting the hook and passing through both of said registering openings so as to lock the guard member in said closed position, said link when in the load carrying position being held within the locking aperture in the shank by the restricted outlet thereof and when turned to a predetermined non-load carrying position being movable out of the locking aperture in the shank through the restricted opening thereof so as to allow the guard member to be moved outwardly to open the hook for the insertion or removal of a sling.

In testimony whereof I affix my signature.
HARRY B. PRETLOVE.
